Attorney.

UNITED STATES PATENT OFFICE.

GEORGE N. MASON, OF READING, PENNSYLVANIA, ASSIGNOR TO READING HARDWARE CORPORATION, OF READING, PENNSYLVANIA, A CORPORATION OF PENNSYLVANIA.

DOOR LOCK.

Application filed May 12, 1927. Serial No. 190,698.

This invention relates to improvements in door locks, and it pertains more particularly to locks in which a dead bolt and a latch bolt are utilized, and in which both of said bolts 5 are capable of actuation by a key operated cam.

The invention is intended primarily to provide means for actuating the bolts irrespective of the position of the dead bolt 10 when the key is applied to the cam cylinder, as for instance when the dead bolt, for any reason, has been only partially thrown.

The invention contemplates a latch bolt 15 operating lever pivotally mounted upon and slideable with the lock or dead bolt.

The invention is more fully described in the following specification and clearly illustrated in the accompanying drawing, in which:—

20 Figure 1 is a back view of a portion of the lock casing, with the back plate removed and showing both dead bolt and latch bolt in the "shot" or locked position.

25 Figure 2 is a sectional view through 2—2 Fig. 1.

Figure 3 is a view similar to Figure 1, but with the dead bolt partially "shot".

30 The numeral 1 designates the casing, 2 the dead bolt and 3 the latch bolt, which latter is backed by a spring 4 to keep it normally "shot". 5 designates the key cylinder and 6 the bolt actuating cam.

35 The dead bolt is provided with a pivoted lever 7, such as is disclosed and claimed in Letters Patent No. 892,347, which patent made provision for engagement of the dead bolt by the cam, irrespective of the position of the dead bolt.

40 In the present instance I apply this structure to a lock in which both the dead bolt and the latch bolt are actuated by the cam action, and to do this I provide a two part latch bolt lever 8—9, both of which are pivotally mounted on and slideable with the 45 dead bolt.

45 The member 8 is formed with a curved, depending portion 10 in engagement with the latch bolt, and, at its opposite end, with a right angled lug 11, extending across the path of, and contacting with the one end of the member 9, whose other end lies within

the path of and is capable of being depressed by the cylinder cam.

The numeral 20 designates the tumbler carried by the dead bolt, and 21 is a spring backed lever, pivotally mounted on and carried by the dead bolt, and this lever is formed with a heel 23 at its free end, which heel forms the forward or outer wall of the cam engaging throat. The spring 22 keeps 60 the heel end of the lever normally in raised position, as shown.

Assuming the parts to be as shown in Figure 3, that is, with the dead bolt partially thrown or "shot". With the parts in this 65 position, and with the lever members 8 and 9 mounted on studs on the casing, instead of on studs on the lock bolt itself, it would be impossible to actuate the lock, because the cam would, when it contacted with the member 9, stop in its rotary movement and could not engage and depress the end 23 of the lever 21. In the present instance however, the cam contacts with the member 9, and the continued movement of the cam will force 70 the dead bolt out until the cam passes it, when it will be free to engage the free end of the lever 21, depress it, and allow the cam to enter the throat of the dead bolt and draw it into its inner or un-locked position, and another revolution of the cam will actuate the levers 8 and 9 and withdraw the latch bolt.

75 It is seen therefore, that no matter where the dead bolt may be, the cam will in its 85 ordinary travel, bring the parts into proper position for actuation by first placing the dead bolt into proper operable position, and then actuating both the dead bolt and the latch bolt.

80 This object, as stated, is accomplished by mounting the pivoted levers 8 and 9 upon studs on the dead bolt, instead of on the casing, in which latter case the cam action would be blocked when the dead bolt was 95 accidentally thrown only a part of its normal distance, while in the present instance the spring-backed movable lever 21 permits the cam to enter the throat of the dead bolt and then actuate the bolt in the usual manner.

90 What I claim is:—

100 In a door lock having a dead bolt, a

spring-backed latch bolt, and levers carried by the dead bolt through which the latch bolt may be actuated; a spring backed lever, pivoted on and carried by the dead bolt, a bolt actuating cam, said spring backed lever having a heel on its inner or free end which heel forms one of the walls of the cam engag-

ing throat of the dead bolt and which heel is capable of being depressed whereby the cam may enter said throat at all points of projection of said bolt. ¹⁰

In testimony whereof I affix my signature.

GEORGE N. MASON.
